GRINDING DISK

Ingle R. Shue, Beloit, Wis., assignor to Gardner Machine Company, Beloit, Wis., a corporation of Illinois

Original application May 25, 1931, Serial No. 539,858. Divided and this application August 10, 1931, Serial No. 556,049

8 Claims. (Cl. 51—209)

The present application is a division of applicant's copending application, Serial No. 539,858, filed May 25, 1931.

The invention relates generally to grinding wheels, and more particularly to wheels of the disk type.

The general object of the invention is to provide a new and improved grinding disk which may be readily attached to a supporting wheel, which is strong and not subject to cracking, and which is so constructed that a maximum use of the abrading material is possible.

More specifically, the object is to provide a grinding disk of this character having a strengthening and securing means moulded therein which is adapted to distribute the stress on the disk over the entire flat area of the disk, said strengthening and securing means being so positioned in the abrading material that it occupies a minimum depth in the rear face of the disk.

Another object is to provide a disk of this character which may be readily attached to a supporting wheel in a grinding machine where only the front or top face of said wheel is readily accessible.

Other objects and advantages will become apparent from the following description taken in connection with the accompanying drawing, in which:

Figure 1 is a fragmentary sectional view, taken on the line 1—1 of Fig. 3, of a disk embodying the features of the invention.

Fig. 2 is a fragmentary view of the right-hand face of the disk shown in Fig. 1.

Fig. 3 is a rear face view on a reduced scale of the supporting wheel.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The present embodiment of the invention comprises generally a supporting wheel which is adapted to be secured to a driving means, and a grinding disk made of abrading material and positioned with its rear face against the supporting wheel. Embedded in this face of the grinding disk and coextensive therewith is a means, such as a wire mesh, for strengthening the abrading material. Means is provided for clamping the grinding disk to the supporting wheel whereby the torsional stress will be transmitted from the supporting wheel directly to the strengthening means and the stresses due to centrifugal force will be resisted by the strengthening means,

said clamping means being conveniently accessible and so positioned as to permit of use of the major part of the abrading material in the disk.

As shown in the drawing, a supporting wheel 10 is provided which is adapted to be secured to a driving means, as by screws (not shown) passing through holes 11 in the central portion of the supporting wheel 10 and adapted to be threaded into a flange on the driving spindle of a grinding machine (not shown). Positioned with its rear face against the supporting wheel 10 is a grinding disk 12 made of molded abrading material.

To strengthen the grinding disk 12 and to prevent any part of it from cracking due to excessive stresses or to expansion, means is provided which is embedded in the abrading material. In the present instance this means comprises a wire mesh 13 which is embedded in the rear face of the grinding disk 12, and which extends to the periphery of the grinding disk so that the edge of the latter will not crack off. The abrading material fills the interstices of the wire mesh so as to form an intimate bond therewith. By positioning the wire mesh in the rear or inner face of the grinding disk, a maximum use of the abrading material is permitted before the disk need be discarded or before additional abrading material need be moulded thereon.

As mentioned above, the invention also includes means for clamping or attaching the grinding disk 12 to the supporting wheel 10 whereby the torsional stress, when the wheel is driven, will be transmitted from the supporting wheel directly to the strengthening means in order to distribute this stress over the whole transverse area of the abrading material. By such distribution of the stress, there is no localization of the latter at definite points, which might tend to crack the abrading material, especially adjacent the periphery thereof.

In the embodiment shown in Figs. 1 and 2, the clamping or attaching means comprises embedded members and removable members cooperating therewith. The embedded members, in the present instance, comprise a plurality of suitably spaced washers 14 embedded in the abrading material and in contact with the inner face of the wire mesh 13. Concentric with the respective washers 14 are a plurality of openings 15, each of which extends through the abrading material to the front face thereof and is adapted to receive the removable member, such as a screw 16, which extends through the washer 14 and an interstice in the wire mesh and is threaded into the supporting wheel 10. Thus, the screws 16 are insertable from the front face, and the disk is convenient for use on a machine where the rear face of the supporting wheel is not readily accessible.

Each washer 14 is of a sufficient diameter to

extend over the wire forming said interstice, and the head of the screw is countersunk into the washer. Thus, the screws 16 cause the washer 14 to bear against the front face of the wire mesh 5 to clamp the mesh against the supporting wheel 10, permitting the stress from the supporting wheel to be transmitted directly to the mesh. The openings 15 need only be large enough to permit the screws 16 to be readily inserted, and 10 preferably are smaller in diameter than the washer 14.

From the above description, it will be apparent that I have provided a grinding disk which can not easily be cracked, since the wire mesh distributes the stresses over the whole area of the grinding disk and the securing devices clamp the mesh directly to the supporting wheel at properly spaced points.

I claim as my invention:

20 1. A grinding element comprising, in combination, a disk of bonded abrasive material, a wire mesh embedded in said disk, and a plurality of washers embedded in the abrading material against the inner face of the wire mesh, said disk having a plurality of openings moulded therein and concentric with the respective washers, said openings being formed for the reception of securing members adapted to bear against said washers and to extend through the mesh.

30 2. A grinding element adapted to be secured to a supporting disk comprising, in combination, a grinding disk made of bonded abrading material and adapted to be positioned with one face against said supporting disk, a wire mesh embedded in said grinding disk, and a plurality of washers embedded in the abrading material against the inner face of said mesh, said grinding disk having a plurality of openings moulded therethrough concentric with the respective washers, each of said openings being formed for the reception of a screw adapted to be threaded in said supporting disk and to extend through an interstice of the mesh and to have its head bear against the washer to clamp the mesh to said 45 supporting disk.

3. A grinding element comprising, in combination, a disk of abrasive material, a wire mesh embedded in said abrading material, and a plurality of washers embedded in the abrading material against one face of said wire mesh, said disk having a plurality of openings molded therein concentric with the respective washers and of smaller diameter than said washers, said openings being formed for the reception of securing means adapted to bear against said washers and to extend through the mesh.

4. A grinding element comprising, in combination, a disk of abrasive material, a wire mesh embedded in said disk, and a plurality of washers 60 embedded in the abrading material against the inner side of said wire mesh, said disk having a plurality of openings molded therein concentric with the respective washers and extending from said washers to the outer face of said disk, said openings being smaller than the diameter of said washers and being formed for the reception of securing members adapted to bear against said washers and to extend through interstices of the mesh.

70 5. A grinding wheel comprising, in combination, a supporting wheel, a grinding disk made of bonded abrading material and positioned with one face against said supporting wheel, sheet-

like reinforcing means moulded to said grinding disk, a plurality of washers embedded in the abrading material against the inner face of said reinforcing means, said grinding disk having a plurality of openings molded therethrough concentric with the respective washers, and a plurality of screws inserted in said openings and extending through the reinforcing means and threaded in said supporting wheel, said screws having their heads countersunk into said washers. 80

6. A grinding wheel comprising, in combination, a supporting wheel, sheet-like reinforcing means, a grinding disk made of bonded abrading material moulded to said reinforcing means, a plurality of washers embedded in the abrading material against the front face of said reinforcing means, said grinding disk having a plurality of openings extending from the front face of said reinforcing means to the front face of said grinding disk and concentric with the respective washers, and a plurality of screws adapted to be inserted in said openings and extending through the reinforcing means and being threaded into said supporting wheel. 90

7. A grinding wheel comprising, in combination, a supporting wheel, a grinding disk made of bonded abrading material and positioned with one face against said supporting disk, a wire mesh embedded in the grinding disk, a plurality of washers embedded in the grinding disk against the front face of said wire mesh, each washer extending over the wires forming an interstice of said mesh, said grinding disk having a plurality of openings extending from said wire mesh to the front face of said grinding disk, and a plurality of screws adapted to be inserted through said openings, each of said screws being threaded into said supporting wheel with its head bearing against one of said washers and with its shank 105 passing through the interstice over which the washer extends.

8. A high-speed, heavy-duty grinding wheel comprising, in combination, a rigid supporting wheel, a grinding disk of molded material positioned against one face of said supporting wheel, means for reinforcing said disk against centrifugal stresses in operation, comprising a sheet of coarse wire mesh embedded in the molded disk adjacent the rear face thereof, and two part 120 means for securing said disk to said wheel comprising a plurality of washers positioned in spaced relation in the molded disk and overlying the inner face of said wire mesh, said disk having a plurality of openings, one for each washer, extending to the front face of the disk, and a plurality of screws, one for each washer, bearing against the respective washers and threaded into the supporting wheel, said wire mesh being composed of heavy strands woven to form large interstices which are dimensioned so that each of 125 said screws may pass through an individual interstice without severance of any of such strands and so that each of said washers overlies the strands of the mesh which together form the sides 130 of a single interstice, the tightening of said screws acting to clamp the mesh sheet and the molded disk as a unit to said supporting wheel, said mesh-sheet lying substantially in a plane without sharp bends in the sheet and thereby serving to afford maximum resistance to centrifugal stresses 135 in the disk by linear tension of the individual strands of said sheet.

INGLE R. SHUE.
